TOY SEWING MACHINE OR SIMILAR ARTICLE

Jarvis W. Rockwell, Chicago, Ill., assignor to Playskool
Manufacturing Company, Chicago, Ill., a corporation of
Illinois

Filed July 5, 1966, Ser. No. 2,942

Term of patent 14 years

(Cl. D34—15)

FIGURE 1 is a front elevational view of the toy sewing machine showing my new design; the back side is like the front but is a mirror image thereof;

FIG. 2 is a top plan view;

FIG. 3 is an end elevational view;

FIG. 4 is an end elevational view taken from the end opposite that shown in FIG. 3;

FIG. 5 is a front elevational view of the toy sewing machine which is identical in all respects to the embodiment shown in FIGS. 1-4 except for the addition of another spindle and a bubble containing a ball on the top of the machine.

The dominant portions of the design reside in the portions shown in full lines.

I claim:

The ornamental design for a toy sewing machine or similar article, as shown and described.
